[57] ABSTRACT

This detent positioning device for orienting and locking a rotary member rigid with a cam in one or more angular positions comprises a roller follower engaging the contour of said cam and adapted to engage a notch under the control of a hydraulic actuator incorporating spring means in its piston rod and, between said rod and the roller, a strap rigid with the rod and a rocker pivoted to said strap and supporting the roller. The arrangement is such that in case of alignment of the three points consisting of the axis of rotation of said rotary member, of the cam dead center and of the axis of rotation of said roller, this alignment is broken automatically by the device.

DETENT POSITIONING DEVICE

FIELD OF THE INVENTION

This invention relates in general to detent positioning devices.

DESCRIPTION OF THE PRIOR ART

It is known to set angularly and lock a rotary member in one or a plurality of angular positions by using a cam mounted on the rotary member and an actuator urging a roller against the cam peripheral contour.

Although this popular arrangement is particularly simple it is objectionable in its various known forms of embodiment in that the assembly is usually wedged when the roller carried by the actuator piston rod engages the top dead center of the cam.

In fact, in these known devices and in this specific position the three points corresponding to the axis of rotation of the shaft or member to be controlled, to the top dead center of the cam and to the axis of rotation of the roller are aligned: therefore, no lateral component force is available for urging the cam (and all the more the shaft or other member rigid therewith) for rotation in one or the other direction.

SUMMARY OF THE INVENTION

It is the essential object of the present invention to avoid the inconvenience set forth hereinabove by providing means whereby the above-defined three points are put automatically out of alignment when said top dead center position is attained.

To this end, the detent-positioning roller is carried by a rocker pivotally mounted in a strap rigid with the outer end of the actuator piston rod, said rocker being responsive to the action of spring means incorporated in said outer end of the piston rod.

In addition to the elimination of any possibility of wedging the parts when the roller is clearing the top dead center position, this device is advantageous in that it ensures an accurate detent positioning of the rotary member in the angular position or positions contemplated when the roller engages a bottom dead center of said cam.

Further advantages and features of this invention will appear as the following description proceeds with reference to the accompanying drawings illustrating diagrammatically by way of example a typical form of embodiment of the device of this invention.

In the drawings:

BRIEF DESCRIPTION OF THE DRAWING

FIG. 1 is a part-sectional, part-elevational view of the rotary member and its detent positioning device, the section being taken at right angles to the axis of said rotary member and devices;

FIG. 2 is a part-sectional view, the section being taken along the line II-II of FIG. 1;

FIGS. 3a, 3b, 3c show in fragmentary and diagrammatic views the positions of the component elements of the device obtaining during three different phases of the detent positioning of the rotary member in a selected angular position; and

FIGS. 4a and 4b are views similar to FIGS. 3a to 3c illustrating two phases of the operation taking place when the roller is clearing a top dead center of the cam.

DESCRIPTION OF THE PREFERRED EMBODIMENT

A rotary shaft 1 has rigidly secured thereto a cam 2, in this specific example a heart-shaped cam having its bottom dead center provided with a symmetric V-shaped notch 3.

Mounted in the structure 4 rotatably supporting the shaft 1 is an actuator 5 comprising (see FIG. 2) a cylinder 6, a bottom 7, a piston 8, a cylinder bottom packing seal 9, a piston packing 10 in the cylinder, a piston-rod packing 11 in the cylinder, and a guide ring 13. A strap 15 secured to the outer end of piston rod 8 carries a rocker 16 pivoted to said strap 15 about a pin 17, the angular excursion of this rocker being restricted by a check pin 18. The rocker 16 rotatably carries a roller follower 19 by means of a pin 20, a needle bearing 21 being interposed between this pin 20 and the roller follower 19. The rocker 16 is constantly urged against the cam 2 or the check pin 18 by a stacking 22 of dished springs guided by an axial rod 23 of a push member 24, a hardened metal plate 25 and a ball 26 being interposed between the push member 24 and rocker 16.

The above-described device operates as follows:

When the piston 8 is moved downwards by feeding fluid under pressure to the actuator chamber 27, the shaft 1 can rotate freely.

For a convenient analysis of the mode of controlling the shaft 1, the following forces will now be considered:

F_1 = force necessary for obtaining a resultant capable of rotatably driving the shaft 1. This force depends on the resistant torque of shaft 1 and on the slope of the cam outline;

F_2 = force developed by the stacked springs 22 in their flat condition, and

F_r = maximum thrust exerted by the actuator in the direction of the cam 2.

The construction according to this invention implies the requirement:

$$F_r > F_2 > F_1$$

When fluid under pressure is fed to chamber 27, assuming that the shaft 1 is stationary, the assembly comprising the piston rod, the strap and the rocker is moved bodily towards the cam and the roller follower 19 engages the cam outline (FIG. 3a). If under these conditions, the roller 19 engages the cam outline at a point other than its top dead center, since the force F_1 alone is sufficient for controlling the cam rotation, the springs 22 are substantially unstressed and the rocker 16 remains in engagement with the check pin 18.

The shaft 1 begins to rotate and this movement continues until the roller 19 engages the V-shaped notch 3 at the bottom dead center of cam 2 (FIG. 3b). The rotational movement is discontinued, as the roller 19 acts as a lock bolt in said V-shaped notch 3 of cam 2. The roller 19 is held against motion together with the piston 8; therefore, the thrust exerted by the actuator increases up to a maximum force F_r . Since this force F_r is greater than the force F_2 developed by the stacked springs 22, these are compressed home, and the piston 8 and strap 15 continue their movement towards the cam, thus causing the rocker 16 to pivot about its fulcrum pin 17 until its opposite end 29 abutes the bottom of strap 15. During this pivotal movement of rocker 16,

the roller 19 moves the cam 2 and shaft 1 to the right, as seen in the drawing, to their final angular position. This position illustrated in FIG. 3c is extremely precise and reproducible since the roller position is strictly subordinate to the dimensions of the triangle having its apexes at the point of contact between the roller follower 19 and the cam 2, the axis of pin 17 and the point of engagement of the rocker end 29 with the strap bottom. The locking torque exerted on the shaft in this position depends on the maximum value F_r , and besides the angle of the V-notch 3 in the cam may be determined at will without taking into account the value of F_2 .

If the roller follower 19 engages the top dead center of cam 2 (FIG. 4a) the force F_1 is applied to the point of contact between roller 19 and cam 2, and the shaft 1 is not rotated since the three points, i.e., shaft center top dead center and roller axis, are aligned. The thrust exerted by the actuator then increases up to the value F_r , the stacked springs 22 are compressed and the strap 15 is moved downwards. Then the rocker 16 pivots about its pin 17 and leaves the check pin 18 (FIG. 4b). During this rocker movement the point of contact of roller 19 with the cam outline is shifted to the right. Immediately as this point of contact is no more coincident with the top dead center of the cam, the aforesaid three points are no more aligned and the shaft 1 begins to rotate. During the first portion of this rotation the rocker 16 resumes its initial position of engagement with check pin 18, the spring stacking is expanded and the thrust exerted by the actuator drops from F_r to F_1 . This rotation is continued until the roller 19 engages the V-shaped notch of cam 2. Then, the detent positioning action is obtained as explained hereinabove.

The chain-dotted cam contour 30 of FIG. 1 shown a modified form of embodiment of this invention giving two predetermined angular and locking positions for a same shaft.

This cam 30 comprises two top dead centers and two bottom dead centers. A specific and advantageous feature of this cam is that the detent position time is reduced to one-half in comparison with the preceding form of embodiment. In fact, the maximum angle of rotation required with this cam 30 is 90° , as contrasted with the 180° necessary with cam 2. However, this modified arrangement is applicable only if a shaft position of $+$ or -180° is contemplated in the desired mode of operation.

It is also possible to contemplate n angular positions for a shaft provided with a cam comprising only one V-shaped notch 3, by radially disposing n actuators about this cam.

Of course, many modifications and variations may be

brought to the specific forms of embodiment and constructional details described, illustrated and suggested hereinabove, without departing from the basic principle of the invention. Thus, notably, it would not constitute a departure from this principle to use any other means for automatically breaking the alignment of the dead center of the cam between the axes of rotation of the shaft and roller, when the cam is in its dead center position.

10 What is claimed as new is :

1. Detent positioning device for orienting and locking a rotary member in one or a plurality of angular positions, which comprises a rotary member a cam rigid with said rotary member, a roller follower engaging the outline of said cam, an actuator urging said roller follower against said cam outline, and means for automatically displacing the point of contact between the cam and roller so as to shift this point of contact in relation to the plane containing the axes of the rotary member and of the roller, when said roller is at the top dead center of the cam.

2. Detent positioning device for orienting and locking a member rigid with a shaft adapted to revolve freely, which comprises a cam rigid with said shaft and having at least one dead center whereat the distance from the cam outline and the axis of said shaft has its minimum value, a hydraulic actuator having its piston rod directed towards the shaft axis, a push member slidably mounted in the piston rod of said actuator, spring

25 means mounted in said piston rod coaxially to said push member for constantly urging said push member towards said cam, a strap rigid with said piston rod and having a bottom facing said cam, a pivot pin and a check pin mounted across said strap, a rocker mounted for free pivotal motion in said strap about said pivot pin and movable angularly between a lower position in which it engages the bottom of said strap and an upper position in which it abutes said check pin, a roller follower rotatably mounted on said rocker and adapted to engage the outline of said cam through the combined action of said actuator and said spring means, said rocker being adapted to remain in said upper position in said strap as long as the actuator force is inferior to the force of said spring means, and to assume its lower position in said strap while tending to release said roller from said cam outline when the actuator force becomes greater than the force of said spring means.

3. Device as set forth in claim 2, wherein said cam comprises a single dead center, in combination with n actuators disposed radially about said cam and adapted to lock said rotary member, for each rotational movement thereof, in n different angular positions.
